MONITORING SUPERVISION ON PARTY LINES IN AUTOMATICALLY-OPERATED TELEPHONE EXCHANGES.

Application filed November 27, 1925. Serial No. 71,651.

This invention relates to a telephone exchange system and more particularly to a monitoring system for lines associated with a machine switching system.
 5 Lines extending from a telephone office become faulty from weather conditions, station set troubles or are removed from service for various reasons. In a telephone office of the automatically operated type, calls for such lines must be received by an operator in order that the calling subscriber be advised of the condition of the called line. Where the calling line has call charging apparatus associated therewith a difficulty arises in answering such calls in a manner to prevent the operation of the call charging apparatus. This difficulty is increased where the lines out of service are party lines, since the talking battery used for the operation of call charging apparatus is reversed, with relation to the line conductors, for the different parties. A further control difficulty arises on account of the talking battery supply which may vary for different types of service.
 15 It is an object of this invention to provide an improved method of monitoring on party lines extended through automatic switches.

A feature of this invention is the provision of means in an automatically operated telephone exchange for monitoring and supervising telephone calls from service charge lines to faulty party lines in a manner to prevent a charge for such calls.
 30

While the invention has been disclosed as particularly adapted for monitoring on party lines associated with machine switching offices, it is apparent from the following description that the invention has a wider utility and by slight modification it could be adapted for purposes other than monitoring.
 35

Referring to the drawings, Figs. 1, 2 and 3 inclusive illustrate diagrammatically machine switching apparatus necessary for establishing a telephone connection from substation A shown in Fig. 1 to a party line having subscriber's stations B and C shown in Fig. 3. The right hand portion of Fig. 3 and Figs. 4 and 5 illustrate the circuits associated with such a party line for monitoring purposes.
 45

Fig. 1 illustrates a subscriber's station A

and call charging apparatus associated therewith. The line apparatus and line brushes 55 103, 104 and 105 illustrate diagrammatically a line switch for selecting a district selector as shown in the main portion of Fig. 1. The sender is diagrammatically shown enclosed by dotted lines in the lower portion 60 of Fig. 1.

Fig. 2 illustrates an incoming selector circuit selectable by a district selector and controllable by a sender for selecting a final selector shown diagrammatically in the left hand portion of Fig. 3.

Fig. 3 illustrates a faulty line associated with subscribers' stations B and C with the heat coils removed from the arrester 340 in order to permit the association of plug 342 70 in a manner to connect the line terminals 303 and 304 with the monitoring circuit separately from the connection of the line conductors and stations B and C with the monitoring circuit. The right hand portion of 75 Fig. 3 illustrates a plugging up circuit arranged with apparatus responsive to various conditions associated with the line conductors or with the conductors associated with the final frame.
 80

Figs. 4 and 5 illustrate a monitoring cord circuit arranged to monitor and supervise faulty lines or telephone calls for such lines extended through the automatic switches of the telephone office.
 85

Fig. 6 is a diagram showing the manner in which the several sheets of the drawing should be organized.

The selector switch equipment and sender disclosed herein are the same in operation as 90 those disclosed in Patent 1,505,171 to F. A. Stearn. The district selector and line switch with associated call charging apparatus, are described in detail in Patent 1,491,323 to D. L. Temple.
 95

General description.—The operation of a full mechanical telephone office of the re- 100 vertive impulse type illustrated in the drawings of Figs. 1 and 2 is well understood in the art. A description of the line conditions associated with apparatus of this type will be given.

The ringing apparatus of an incoming selector switch, Fig. 2, is the same for single party lines as it is for two-party lines. 105 However a change is made in the group cross

connections at the final frame when two-party lines are associated with a telephone office of this type. The two party line stations such as B and C are connected to the same line conductors but are not connected to the same terminals upon the final frame. A reversal of the conductors between the main frame arrestor, such as 340, is made in order that the ringing current from the incoming selector may be associated properly with the line conductors to actuate the bell at stations B or C. This reversal of the conductors between the final frame and the main frame further reverses the association of talking battery with the line conductors for different parties on the same line.

When a faulty line is reported the heat coils are removed from the arrestor and a plug such as 342 is associated with the arrestor, and plugs 313 and 314 are inserted into a set of monitoring jacks such as 319 and 320 in order to actuate signals appearing before a monitoring operator responsive to calls for or from said line and permit supervision and tests of such lines.

When telephone calls from subscribers' stations such as station A are initiated for station B or C a final selector such as 300 is directed to the final frame line terminals 303 and 304 or 344 and 345. It will be noted that the conductors associated with these terminals are extended through the plug 342 to the monitoring apparatus instead of to the line conductors in order that a call initiated by a subscriber for a wanted line which is faulty may be answered by the monitoring operator.

40 Relay 324 is operated by the ringing current associated with the tip and ring conductors of the incoming selector and the operation of this relay illuminates a lamp to signal the monitoring operator that a call has been received for a faulty subscriber's station. In response to such a signal the monitoring operator inserts plug 400 into jack 325. Apparatus in the monitoring cord circuit of Figs. 4 and 5 is now actuated to trip the ringing current apparatus in the incoming selector. When the ringing current is tripped the sequence switch of the incoming selector advances to talking position to associate talking battery with the talking conductors.

55 As described in detail in the patent to
D. L. Temple, No. 1,491,323, the talking
battery is used to actuate the call charging
apparatus and therefore the monitoring cir-
cuit Figs. 4 and 5 must be associated with
the incoming selector in such manner that
60 the supervisory relay 259 will not be oper-
ated.

Detailed description.—Assuming that the line associated with stations B and C is faulty or that there is a fault in one of said stations, plug 342 is associated with arrestor

340 as shown in Fig. 3. It will be noted that the association of this plug with the arrestor separates the stations and line from the conductors associated with the final frame. Plugs 313 and 314 are inserted in jacks 319 and 320 respectively. The stations B and C are now associated with jack 326. The final frame terminals 303 and 304 70 344 and 345 are associated with jack 325. Insertion of plug 313 into jack 319 establishes a circuit to operate relay 329 over an obvious circuit. The operation of relay 329 75 establishes a circuit through the filament of the green lamp 328 to indicate to the monitoring operator that this apparatus is associated with a faulty line. 80

Let it now be assumed that a call is initiated at station A for station B. The line switch, selects the district selector Fig. 1, which associates a sender therewith for positioning the district selector and other switches in the manner fully described in Patents 1,505,171 and 1,491,323 hereinbefore mentioned. The incoming selector switch Fig. 2 is now positioned to select the final selector 300 and the final selector switch is controlled to associate its brushes with terminals 303 and 304. Upon the selection of these terminals the sequence switch of the incoming selector Fig. 2, is rotated to a position for the association of ringing current with the ring conductor which is the normal function for actuating the bell at the subscriber's station B. Since the conductors from the final frame are associated with the monitoring apparatus, Fig. 3, instead of with the subscriber's station this ringing current is associated with relay 324 instead of the ringer winding at the subscriber's station. This circuit may be traced from the alternating current source 254 through the interrupter 256, right lower and upper contacts of cam 217, tripping relay 255, lower contacts of cam 202, right contact of relay 221, which is in an operated position, right lower contact of cam 214, brush 248, terminal 249 and thence through the apparatus or the final selector switch to brush 302, terminal 304, springs 308 and 312, conductor 318, sleeve of plug 314, sleeve of jack 320, conductor 321, ring contact of jack 325, right winding of relay 324, condenser 334, tip contact of jack 325, conductor 335, sleeve of jack 319, sleeve of plug 313, conductor 316, springs 311 and 307, terminal 303, brush 301, thence through the apparatus of the final selector switch to terminal 247, brush 246, to ground through the right upper contact of cam 213. The energization of relay 324 establishes a locking circuit for the relay from ground through the lower contact of jack 325, left winding and left inner contact of relay 324 to battery through the right inner contact of relay 329. A circuit is further established to illuminate white 130

- lamp 327 from ground, through its filament, left outer contact of relay 324 to battery through the right inner contact of relay 329.
- 5 The illumination of the white lamp 327 is an indication to the monitoring operator that a call has been received through the automatic switches for the faulty line associated with the plugging up apparatus indicated by said lamp. To answer such a call, plug 400 is inserted in jack 325 which establishes a circuit for relays 405 and 407 and opens the energizing and locking circuits for relay 324 to extinguish the white lamp 327 and associate the ringing current with the apparatus of the monitoring circuit Figs. 4 and 5. The circuit for energizing relays 405 and 407 may be traced from ground through the sleeve of jack 325, sleeve 20 of plug 400 to battery through the windings of relays 405 and 407 in multiple with the resistance 421. The operation of relay 405 establishes a circuit to energize the winding of relay 507 which may be traced from ground through the contact of relay 405 to battery through the winding of relay 507. The operation of relay 507 establishes an energizing circuit for relay 404 from battery through the winding of relay 404 to ground through the right outer contact of relay 507. The operation of relay 507 further establishes ground circuits to be used for the progressive establishment of circuits for relays 500 to 502 and 504 to 506, inclusive. The operation of relay 407 establishes a circuit to energize the winding of relay 403 from ground through the contact of relay 407, left outer normal contact of relay 409, winding of relay 403 to battery.
- 40 The operation of relay 403 establishes an energizing circuit through the winding of relay 406 from battery through its winding to ground through the right outer contact of relay 403. Relay 406 establishes a locking circuit for itself through its inner contact to ground through the right inner contact of relay 507 and remains operated to prevent the operation of relay 401. Should relay 401 be permitted to operate apparatus 50 of the circuit could energize relay 259.
- The monitoring operator actuates the talking key 414 to associate the monitoring set 423 with the calling subscriber's line. The ringing current must be tripped and the party called determined before the set 55 423 is associated with the calling lines.
- With key 414 operated relay 508 is bridged across the tip and ring conductors to associate the ringing current therewith. The 60 ringing current source and ringing ground has already been traced to the tip and ring springs of jack 325 and thus associated with the tip and ring conductors connected to plug 400. Assuming that brush 302 is as-
- sociated with terminal 304 as previously described the ringing current may be traced through the left normal contact of relay 401, right inner normal contact of relay 402, left contact of relay 403, right normal contact of relay 500, tip contact of talking key 70 414, left normal contact of relay 504, winding of relay 508, right inner contact of relay 403, left normal contact of relay 402, right normal contact of relay 401 to ground at the incoming selector the tip conductor of plug 400. Relay 508 is operated by the ringing current conducted through its winding and establishes an energizing circuit through the winding of relay 509 which may be traced from battery through the winding of relay 509, contact of relay 508, right normal contact of relay 501 to ground through the left outer contact of relay 507. Relay 509 in operating establishes a locking circuit for itself through its left contact to ground 80 through the left outer contact of relay 507.
- The operation of relay 509 establishes an energizing circuit through the winding of relay 504 from battery through its winding, left inner normal contact of relay 500, right outer contact of relay 509, contacts of interrupter 520, left normal contact of relay 502, left normal contact of relay 503 to ground through the left inner contact of relay 507. Interrupter 520 is continuously operated at intervals of proper duration for the establishment of the circuits traced. The operation of relay 504 establishes a locking circuit for itself and an operating circuit for relay 500 which is effective when interrupter 520 opens its contact. This circuit may be traced from battery through the windings of relays 504 and 500, right contact of relay 504, left normal contact of relay 503 to ground to the left inner contact of relay 507. A ground shunt is maintained around the winding of relay 500 during the closed period of the interrupter contacts since ground is associated with one end of the winding through interrupter 520 and associated with the other end of the winding through the right contact of relay 504, left normal contact of relay 503 and left inner contact of relay 507. When the contact of interrupter 520 is opened the shunt is removed to allow the energization of the winding of relay 500.
- The operation of relay 504 disestablishes the circuit through the winding of relay 508 and the operation of relay 500 bridges the resistance 521 across the tip and ring conductors in order to energize the tripping relay 255 to disconnect ringing current from the monitoring circuit. The tripping circuit may be traced from the ring conductor of plug 400 through the left normal contact of relay 401, right inner normal contact of relay 402, left contact of relay 403, right contact 120 125

of relay 500, resistance 521, left normal contact of relay 505, right inner contact of relay 403, left normal contact of relay 402, right normal contact of relay 401, to the tip conductor of plug 400.

The operation of tripping relay 255 in the well known manner, opens the holding circuit for relay 221 and the release of relay 221 establishes an energizing circuit for sequence switch magnet 200 which rotates the sequence switch into a position where the talking battery is associated with the tip and ring conductors through the right windings of the repeating coil 258.

15 The brushes of the final selector may be associated with the terminals of either party line indicated by terminals 303, 304, 344 and 345. If brushes 301 and 302 are associated with terminals 303 and 304, the ungrounded 20 pole of talking battery is associated with the arrestor spring 308 and talking ground with spring 307. If brushes 301 and 302 are associated with terminals 344 and 345, the ungrounded pole of talking battery is associated 25 with arrestor spring 307 and talking ground with arrestor spring 308. Since the operation and release of supervisory relay 259 establishes a circuit to actuate the call charging apparatus of the calling line, means must be provided in a monitoring circuit to prevent the operation of the supervisory relay in order not to charge the subscriber for a call to a faulty line.

30 Apparatus in the monitoring circuit is now operated to determine the conductor to which talking battery is connected in order to further operate the apparatus of this monitoring circuit in a manner to prevent the operation of the supervisory relay. It will be remembered that the initial closure of interrupter 520 operated relay 504 and its opening removed a shunt path from relay 500 to allow it to operate for the establishment of the tripping bridge through resistance 521. A subsequent closure of interrupter 520 establishes a circuit for the operation of relay 505 from grounded battery through its winding, left normal contact of relay 501, left inner contact of relay 500, right outer contact of relay 509, contact of interrupter 520, left normal contact of relay 502, left normal contact of relay 503, to ground through the left inner contact of relay 507. The operation of relay 505 removes the tripping bridge and establishes a locking circuit for itself and an operating circuit for relay 501 which is effective upon the opening of the interrupter contacts. The shunt around the winding of relay 501 is maintained by closure of interrupter contacts in the same manner as described for relay 500. Upon a subsequent opening of the interrupter contact the operation of relay 501 takes place.

65 The operation of relay 501 opens the lock-

ing circuit for relay 509 traced through its right contact and establishes a circuit for the operation of relay 506 upon a subsequent closure of interrupter 520. The operating circuit for relay 506 may be traced from battery through its winding, left contact of relay 501, left inner and outer contacts of relay 500, interrupter 520, left normal contact of relay 502, left normal contact of relay 503 to ground through the left inner contact of relay 507. The operation of relay 506 establishes a locking circuit for itself and an operating circuit for relay 502 in the manner previously described for relays 505 and 501. The operation of relay 506 further establishes a ground for holding the relay 509 if it should operate and associate a ground through its left contact with one end of the winding of relay 508.

70 The ground is associated with the winding of relay 508 in order to test the tip conductor for talking battery. If talking battery is connected to the tip conductor an operating circuit for relay 508 is established from this ground, through its winding, right inner contact of relay 403 left normal contact of relay 402 right normal contact of relay 401, tip conductor of plug 400, tip spring of jack 325, sleeve of plug 319, sleeve of plug 313, conductor 316, spring 311 of plug 342, spring 307 of arrestor 340, terminal 345 to talking battery over the ring conductor of the incoming selector. To receive talking battery in this manner it would of course be necessary that the final selector brushes 301 and 302 be associated with the final multiple terminals 344 and 345 representing one party of a party line. If the talking battery is received at the monitoring circuit over the ring conductor, the relay 508 is not associated with a talking battery and therefore its winding is not energized and since relay 508 is not energized a circuit for relay 509 is not established. The holding circuit for relay 509 is thus not established. The non-completion of a circuit for relay 508 indicates that the talking battery is connected to the ring conductor of the monitoring circuit and that the final selector brushes are connected to terminals 303 and 304.

75 Upon a subsequent opening of the contact of the interrupter 520 relay 502 operates from battery through the windings of relay 506 and 502, right inner contact of relay 506 to ground through the left outer contact of relay 507. The operation of relay 502 removes the ground circuit from interrupter 520 at its left contact and prepares an operating circuit for relay 510 through its right inner contact. It further establishes an operating circuit for relay 409 from battery through its winding, right outer contact of relay 502 to ground through the left outer contact of relay 507. The energizing circuit for relay 403 is opened through the left

outer contact of relay 409 to cause its release.

Let it be assumed that the final selector switch brushes are connected to terminals

- 5 344 and 345 and that talking battery is thus associated with the tip conductor of the monitoring circuit to energize the winding of relay 508. The winding of the relay is of sufficiently high resistance to prevent the
- 10 operation of the supervisory relay 259 when the talking battery is of maximum voltage. The operation of relay 508 establishes a circuit to operate relay 509 from battery through its winding, contact of relay 508,
- 15 right outer contact of relay 506 to ground to the left outer contact of relay 507. Relay 509 is locked through its left contact to the operating ground above traced. The operation of relay 509 further establishes a
- 20 circuit to associate the high resistance left winding of relay 511 with the ring conductor which it is assumed is carried to ground at repeating coil 258. This circuit may be traced from battery through the left
- 25 winding of relay 511, contact of relay 510, right inner contact of relay 509, left inner contact of relay 409, left lower winding of repeating coil 413, left inner contact of relay 404, left normal contact of relay 403,
- 30 right inner normal contact of relay 402, left normal contact of relay 401, ring conductor of plug 400 and thence over a circuit previously traced to terminal 344 brush 301 to the grounded pole of the talking battery at
- 35 repeating coil 258. It will be noted that the tip conductor is opened at the right inner contact of relay 509. It remains open during monitoring to prevent operation of supervisory relay 259.
- 40 The operation of relay 511 establishes an obvious circuit for the operation of relay 503. The operation of relay 503 which prepares a path for the energization of relay 408 whenever the flashing key 422 is operated.
- 45 This circuit may be traced from ground at the left inner contact of relay 507, left contact of relay 503, upper ring contact of key 414, left contact of key 422 to battery through the winding of relay 408.
- 50 The operation of relay 408 in turn establishes an obvious energizing circuit for relay 402 and the release of this key releases both relays. This combination of flashing relays is not used in connection with a call
- 55 through the mechanical switches as hereinbefore described but is used when the circuit is associated with a type of incoming selector switch for a call initiated from a manual office. Since this feature is not a part
- 60 of the invention it will not be further described herein.

The release of relay 403 upon the operation of relay 409, establishes the talking conductor circuits through the left winding of

repeating coil 413. With key 414 actuated 65 the operator's headset is now associated with the calling subscriber who is advised of the condition of the line called.

Assuming that the final brushes 301 and 302 are associated with terminals 303 and 70 304, battery is received in the monitoring circuit over the ring conductor. An energizing circuit for relay 508 is not associated with its winding under this condition. Relay 409 is however operated as before 75 through the right outer contact of relay 502. The ring conductor is opened at the inner contact of relay 409 and the tip conductor which is associated with ground at the repeating coil 258 is extended through the left 80 middle contact of relay 409, right inner normal contact of relay 509, normal contact of relay 510 to battery through the high resistance winding of relay 511. Relay 511 is thus operated to establish energizing circuits for the flashing relays. The energization of relay 503 opens the locking circuits for relays 500, 504, 501 and 505 to cause their release. Relays 502 and 506 remain operated until the release of relay 507. 90

The operation of relay 511 in each of the operations described above extinguishes the lamp 410 which lighted upon the operation of relay 404, to advise the monitoring operator that the talking conductors have been 95 prepared for conversation with the calling subscriber.

When the calling subscriber has been properly informed by the monitoring operator, the receiver is placed upon the switch-hook of the calling station and the mechanical switches are released in a manner described in the aforementioned patents. The release of the incoming selector switch 100 disassociates brushes 246 and 248 from terminals 247 and 249, thus disconnecting the talking battery from the monitoring circuit to cause the release of relay 511 which establishes a circuit to light lamp 410. The illumination of lamp 410 indicates to the 105 monitoring operator that the calling subscriber has disconnected which is a signal for said operator to remove plug 400 from jack 325. The removal of plug 400 releases relays 405 and 407 which in turn release the 110 remaining relays operated for the connection. 115

Should plug 400 be removed from jack 325 by mistake previous to the disconnection of the automatic switches it may again be 120 inserted into the jack and the reoperation of relays in the monitoring circuit Figs. 4 and 5 takes place in the manner previously described with the exception that no ringing circuit is received from the incoming selector switch. The connection of the talking battery to the tip or ring conductor is tested by the monitoring circuit in the man-

ner previously described and the operator's telephone circuit may be associated with the calling subscriber.

Let it be assumed that stations B and C and the line connected therewith are in condition for making a call to the central office and that the subscriber at station B removes the receiver from the switchhook. A circuit is established to energize relay 330 from battery through its winding, contact of jack 326, conductor 322, tip contact of jack 320 and plug 314, conductor 317, spring 310 of plug 342, spring 306 of arrestor 340 and thence over the line loop through the subscriber's station apparatus to spring 305 of arrestor 340, spring 309 of plug 342, conductor 315, tip of plug 313 and jack 319, conductor 323 to ground through the spring of jack 326. The operation of relay 330 establishes a circuit to illuminate red lamp 331 from battery through the right inner contact of relay 329, filament of lamp 331, normal contact of key 332, contact of relay 330 to ground through the contact of jack 326.

The illumination of red lamp 331 is a signal to the monitoring operator that a call has been initiated from a line associated therewith. This call originating from station B may be initiated by a test man or may have been made by a mistake of the subscriber whose line has been taken out of service. The monitoring operator inserts plug 400 into jack 326 which establishes an energizing circuit for relay 405 from battery through its winding, sleeve of plug 400 and jack 326 resistance 350 to ground. It will be noted that relay 407 is included in this circuit, but since it is marginal it does not receive sufficient current through resistance 350 to cause its operation.

The operation of relay 405 establishes an obvious circuit to operate relay 507. The operation of relay 507 establishes a circuit through its right outer contact to energize the winding of relay 404. Relay 404 operates and establishes a circuit from ground through its right inner contact, left normal contact of relay 406, winding of relay 401 to battery. The operation of relays 404 and 401 associates the line conductors from plug 400 through the contacts of relay 401, contacts of keys 412, 411 and 415, normal contacts of relays 402 and 403, contacts of relay 404, left upper and lower windings of repeating coil 413, the tip conductor being carried to ground through the left middle contact of relay 409 and the ring conductor through the left inner normal contact of relay 409, right winding of relay 511 to battery. The right winding of relay 511 is of low resistance in order that talking battery may be supplied over the line loop from the circuit traced. The operation of relays 401, 404, and 511 takes place in rapid succession

which does not allow sufficient time for lamp 410 to become illuminated when its circuit is closed through the right outer contact of relay 404.

The operation of the talking key 414 now associates the operator's head set with the subscriber's station to permit conversation. If a test man has initiated the call he may request the monitoring operator to ring the substation bell. Keys 411 and 412 are included in the circuit for this purpose. Key 411 is for associating ringing current with the subscriber's station of the party requiring connection of ringing current to the ring conductor and key 412 is for associating ringing current with the second station associated with the line requiring ringing current on the tip conductor.

When the receiver is replaced upon the switchhook at the calling station relay 511 is released which establishes an obvious circuit to illuminate lamp 410. Plug 400 is then removed from jack 325 by the monitoring operator and the relays of the monitoring circuit are released.

The monitoring operator may be required to make tests upon the line other than described above, such as tests for grounds connected to the tip or ring conductor, short circuits on the line or in the station apparatus or other tests that may be made with a voltmeter. For such tests plug 400 is inserted into jack 326 which causes the operation of relays as previously described for the operation of the monitoring circuit in answering a call from station B or C. The operation of key 415 now associates the voltmeter circuit with the line conductors. A test for a short circuit may be made by the operation of key 416 to associate ground with the conductors of the line. If a short circuit exists the deflection of the meter is not changed when key 417 is operated to transfer the ground from the tip to the ring conductor. A test for extraneous ground or battery is made by associating the voltmeter with the line conductors, the resistance of which is known. The monitoring operator notes the deflection of the voltmeter needle and operates key 418 which includes resistance 430 to vary the voltage associated with the line conductors to make further voltmeter readings. Other tests well known in the art may be made by the use of this voltmeter.

Upon the completion of all tests plug 400 may be removed from jack 326 to restore the monitoring circuit apparatus to normal.

What is claimed is:

1. In a telephone exchange system, a line, a link circuit, switching means for connecting either conductor of said link circuit with either conductor of said line, a loop circuit including a battery having one pole grounded extending over the conductors of

- said line and link circuit, responsive means in said loop circuit and a testing relay in said line for determining to which conductor thereof the ungrounded pole of said 5 battery is connected without operating said responsive means.
2. In a telephone exchange system, a line, a link circuit, switching means for connecting either conductor of said link circuit with either conductor of said line, a loop circuit including a battery having one pole grounded extending over the conductors of said line and link circuit, responsive means in said loop circuit, means in said 10 line for determining to which conductor thereof the ungrounded pole of said battery is connected, monitoring means, and means responsive to said determining means for connecting said monitoring means with said 15 link without operating said responsive means.
3. In a telephone exchange system, a line, a link circuit, switching means for connecting either conductor of said link circuit with either conductor of said line, said switching means being controlled from a calling station having call charging apparatus associated therewith, a loop circuit including a battery having one pole grounded extending over the conductors of said line and link circuit, responsive means in said loop circuit for actuating said call charging apparatus, means in said line for determining to which conductor thereof the ungrounded 20 pole of said battery is connected, monitoring means, and means responsive to said determining means for connecting said monitoring means with said link without operating said responsive means.
4. In a telephone exchange system, a trunk arranged for differing connections with an automatic switch having a loop circuit including a battery with one pole grounded, responsive means in said loop circuit, and means in said trunk for detecting the ungrounded battery pole in order to prevent operation of said responsive means.
5. In a telephone exchange system, a trunk, a loop circuit including a battery having one pole grounded, switching means for connecting either conductor of said loop to either conductor of said trunk, responsive means in said loop circuit, and means in said trunk for determining to which conductor thereof the ungrounded pole of said battery is connected in order to prevent the operation of said responsive means.
6. In a telephone exchange system, a trunk associated with party line terminals, means in said trunk to receive party line calls initiated by a station having call charging apparatus associated therewith, a selector switch under the control of said 60 station for selecting party line terminals, auxiliary apparatus associated with said 65 auxiliary apparatus.
7. In a telephone exchange system, a trunk associated with party line terminals, means in said trunk to receive party line calls initiated by a station having call charging apparatus associated therewith, a selector switch under the control of said station for selecting party line terminals, auxiliary apparatus associated with said switch for controlling said call charging apparatus, and means automatically operable in response to the association of said switch with said trunk for differentiating between party calls in order to prevent the actuation of said auxiliary apparatus.
8. In a telephone exchange system, a trunk associated with party line terminals, means in said trunk to receive party line calls initiated by a station having a call charging apparatus associated therewith, a selector switch under the control of said station for selecting party line terminals, auxiliary apparatus associated with said switch for controlling said call charging apparatus, means in said trunk for differentiating between party calls in order to prevent the actuation of said auxiliary apparatus, monitoring means, and means responsive to said differentiation for connecting said monitoring means in operable relation with a calling station.
9. In an automatic telephone exchange, a monitoring system, means to connect the apparatus of said monitoring system with a party line in such manner that calls for said line terminate in said apparatus, means in said monitoring system to receive ringing current for the parties of said line, and means to determine which party is called independent of the kind of ringing current received.
10. In an automatic telephone exchange, a monitoring system, means to connect the apparatus of said monitoring system with a party line in such manner that calls for said line terminate in said apparatus, a link circuit, switching means for connecting either conductor of said link circuit with either conductor of said monitoring system, a loop circuit including a battery having one pole grounded extending over the conductors of said link and monitoring system, and means in said monitoring system for determining to which conductor thereof the ungrounded pole in said battery is connected in order to determine which party is called.
- In witness whereof, I hereunto subscribe my name this 12th day of November A. D., 1925.

ARNOLD S. BERTELS.
